UNITED STATES PATENT OFFICE.

ARLINGTON L. BALL, OF DUNKIRK, NEW YORK, ASSIGNOR, BY MESNE ASSIGNMENTS,
TO GERMER STOVE COMPANY, OF ERIE, PENNSYLVANIA, A CORPORATION OF PENN-
SYLVANIA.

LIQUID-FEED DEVICE.

1,339,734.

Specification of Letters Patent. Patented May 11, 1920.

Application filed November 8, 1918. Serial No. 261,622.

To all whom it may concern:

Be it known that I, ARLINGTON L. BALL, a citizen of the United States, residing at Dunkirk, in the county of Chautauqua and 5 State of New York, have invented certain new and useful Improvements in Liquid-Feed Devices, of which the following is a specification.

My invention relates to a liquid feed-device, and more particularly to a device for providing even and constant feed of liquid fuel.

My invention has for its primary object the provision of a simple and efficacious feed 15 controlling device whereby liquid-fuel may be supplied to a fuel-burner; it being particularly designed for use in connection with burners employed in poultry hovers, brooders, etc.; however, it will be understood from the description to follow that it 20 may be adapted for use for various other purposes.

Another object of my invention is to provide a simple float-controlled device having 25 a valve-controlled inlet and a valve-controlled outlet; the device being so constructed that both the inlet and outlet may be closed simultaneously, or that the inlet opening only may be opened and the 30 outlet thereof controlled by the level of the liquid within the device; also so that when the outlet is clogged with foreign matter, this foreign matter will be automatically discharged through the outlet.

35 With these and other objects in view, the invention consists in the novel features of construction and in the arrangement and combination of parts to be hereinafter described and more particularly pointed out 40 in the subjoined claims.

In the drawings:—

Figure 1 is a side elevation of a liquid fuel container having my improved feed-controlling device attached thereto.

45 Fig. 2 is a vertical section through the lower end of the container and the liquid feed-device on a somewhat enlarged scale.

Fig. 3 is an enlarged vertical section through the fuel feed-device and the adjacent portions of the parts to which it is secured.

Fig. 4 is a cross section taken on line 4—4, Fig. 1, looking up.

The reference character 5 designates the 55 liquid fuel container. In the application

of my invention shown in the drawings, this liquid-fuel container is adapted to be positioned in a plane above that in which the burner is located to which the liquid fuel is to be fed evenly and constantly by 60 means of my improved device. This container may be of any construction. In preferred form it, however, consists of a cylindrical casing having a cover 6 which may be removed for providing the container 65 with the desired quantity of fuel.

Secured to the bottom 7 of the liquid-fuel container is a support in the form of a bracket 8, and this bracket has webbed arms 9, 10 arranged at right angles to each other 70 with a lateral guide and sight portion 11 at the lower end of the arm 10. The guide and sight portion of said bracket is provided with a transverse opening 12, preferably closed at opposite ends with glass, as 75 at 13. Threaded into said guide and sight portion from the bottom is a feed pipe 14, which is adapted to be led to the burner which is to be supplied with the liquid-fuel.

Extending upwardly from the transverse 80 opening 12 is a guide opening 15, preferably formed with two diameters joined by a beveled portion or shoulder 16.

17 designates my improved feed controlling device, which comprises a casing or 85 chamber 18 having a cylindrical wall 19, a bottom 20 and a cap or cover 21. The cap or cover 21 has an internally-threaded rim 22 into which the upper externally-threaded end of the body portion of the casing or 90 chamber is to be loosely threaded to any desired degree, for a purpose to appear hereinafter. The cap or cover 21 is provided with an upwardly extending axial boss 23, which extends through the bottom 7 of the 95 container; this boss being soldered, as at 24, around the opening in said bottom through which it is passed. At its upper end the boss 23 is tapered, as at 25, and it is provided with an axial bore, the inner portion 26 of 100 which is considerably larger than the outer portion 27, said portions 26 and 27 being joined by a tapered portion 28, which serves as a valve seat. The bottom 20 of the casing or chamber 18 is provided with a downwardly extending boss 29 adapted to slide within the upwardly extending guide opening 15 in the guide or sight portion 11 of the bracket. 105

Like the boss 23 of the cap or cover 21, 110

the boss 29 is tapered at its lower end, as at 30, and it is also provided with a bore having a portion of comparatively large diameter 31 at its inner end, and a portion of 5 comparatively small diameter 32 at its outer end, said portions 31 and 32 being joined by a tapered portion 33 serving as a valve seat.

Arranged axially within the casing or 10 chamber 18 is a valve rod 34 to which a float 35 is secured. At opposite ends said valve rod is provided with conical valves 36, 37, respectively, the valve 36 being adapted for co-action with the tapered portion or 15 valve seat 28 in the boss of the cap or cover, while the valve 37 is adapted for co-action with the tapered portion or valve seat 33 in the boss 29 at the bottom of the casing or chamber. By preference this valve rod is 20 provided with shoulders 38, 39, respectively, at the bases of the conical valve portions 36, 37 of said rod, and these shoulders are adapted to bear, respectively, against the shoulders 40, 41, formed in the bores of the bosses 25 at the upper and lower ends of the feed device.

This feed controlling-device therefore comprises a chamber or casing having valve seats at its upper and lower ends with comparatively small inlet and outlet openings 30 extending upwardly and downwardly, respectively, a double-ended valve adapted to co-act with said valve seats, and a float controlling the movements of said valve, the 35 whole being arranged to permit of regulating the distance between said valve seats.

When first placing my device into use, the body portion of the liquid-feed controlling 40 device is threaded fully into the cap or cover of said device, as shown in Fig. 3. When thus arranged, the lower valve seat is brought against the lower valve of the valve rod 34, while the upper valve is moved against the upper valve seat, thus closing 45 both the inlet and the outlet openings of the device. The liquid-fuel may now be poured into the container 5, and when filled to the desired height and it is desired to supply the burner with fuel, the body portion is 50 moved downwardly to the desired degree by unthreading the same from the cap or cover to the required extent. During this action, the body portion of the liquid-feed device is moved downwardly while being rotated, thus causing the boss 29 at the lower end 55 thereof to move further into the upwardly extending guide opening 15 in the guide and sight portion of the bracket. At the same time, the valve rod and the float attached thereto move downwardly within the casing or chamber 18 so as to cause the outlet opening of the latter to remain closed. This action permits the valve at the upper 60 end of said valve rod to become unseated from the valve seat formed in the boss 23 ex-

tending into the liquid fuel container. The liquid from the container may therefore pass through the boss 23 and enter the casing or chamber 18.

When the liquid-fuel within the casing 70 or chamber reaches a certain level predetermined by the position of the float on the valve rod, the valve at the lower end of said valve rod becomes unseated and permits the liquid-fuel to pass through the 75 guide and sight portion of the bracket and down through the feed pipe to the burner supplied thereby. The upward movement of the valve rod is comparatively slight but sufficient to somewhat restrict the flow of 80 the liquid fuel through the inlet of the casing or chamber, and when the normal level of the liquid within the casing or chamber is reached, both valves will be exactly equal distances from their seats, 85 thus the flow of the liquid-fuel from the casing or chamber will exactly equal that entering said casing or chamber from the container. The amount of liquid-fuel fed to the burner can be easily ascertained 90 through the sight opening 12 in the bracket, and if the quantity fed is to be reduced, it is simply necessary to rotate the body portion of the casing or chamber 18 to the right so as to slightly shorten the distance 95 between the two valve seats of the device. When more liquid-fuel is necessary for the desired results, the body portion of said casing or chamber may be rotated to the left, thus increasing the distances between 100 the valve seats, and thereby enlarging the spaces between the valve seats and the valves co-acting therewith.

By tapering the upper end of the upper boss, foreign particles coming in contact 105 therewith tend to move away from the inlet opening, thus minimizing the chances of foreign matter entering the casing or chamber 18. If, however, foreign matter should enter said casing or chamber and lodge between the lower valve seat and the valve co-acting therewith, the flow of the liquid fuel through the outlet of the device is 110 consequently reduced. This causes the flow of the liquid fuel entering the device 115 to be greater than the quantity of fuel escaping therefrom, with the result that a higher level of the liquid-fuel will be created within said device, thereby causing the float to rise with the result that 120 the valve at the upper end of the valve rod will close against its valve seat. At the same time, the space between the valve at the lower end of said valve rod and its co-acting seat becomes enlarged so that the 125 liquid fuel passing through the outlet will act to loosen the foreign matter and carry the same down through the guide and sight portion of the bracket and into the feed pipe 14. This causes the level of the liquid- 130

fuel to be lowered within the casing or chamber 18, whereupon the upper valve is moved from its co-acting valve seat and the lower valve moved toward its co-acting valve seat, after which the flow through the inlet and outlet again becomes equalized.

By means of this construction, an even and constant feed is assured at all times, and the quantity of liquid fed into and from the liquid-fuel device can be regulated most minutely, due to the fact that a complete revolution of the body portion of the casing will cause only a slight increase in the space between the two valve seats of the device, and it is apparent that the body portion may be rotated any portion of a revolution of any number of revolutions.

Having thus described my invention, what I claim is:—

1. In a liquid feed-device, an extensible casing having an inlet opening at one end and an outlet opening at its other end, connected valves arranged within said casing and adapted to co-act with said inlet and said outlet openings, and a float to which said valves are connected.

2. In a liquid feed-device, a casing comprising two parts and having one part threaded into the other, one part having an inlet opening provided with a valve-seat and the other part having an outlet opening provided with a valve-seat, a valve-rod arranged axially within said casing and having valves at opposite ends adapted to co-act with said valve-seats, and a float secured to said valve rod.

3. A liquid feed-device, comprising a casing having a body portion provided with an outlet opening at its lower end, a cap into which said body portion is adjustably threaded, said cap having an inlet opening therethrough, and float-controlled valves rigidly connected together and adapted to co-act with said inlet and said outlet openings.

4. A liquid feed-device, comprising a casing having a body portion provided with an

axial outlet opening at its lower end and a valve-seat around said outlet opening, a cap into which said body portion is adjustably threaded and which is provided with an axial inlet opening and a valve-seat around said inlet opening, a valve rod arranged axially within said casing and having valves at opposite ends adapted to co-act with said valve-seats, and a float secured to said valve rod.

5. The combination with a liquid container, of a liquid feed-device secured to said container and comprising a casing having two parts, one part having an axial boss extending up through the bottom of said container and having the upper end of said boss tapered, said boss having an inlet opening axially therethrough with a valve seat around said inlet opening, the other part of said casing being adjustably threaded into the first-mentioned part and having an axial outlet opening in its bottom and a valve seat around said outlet opening, a valve-rod arranged axially within said casing and having valves at opposite ends adapted to co-act with said valve-seats, and a float secured to said valve-rod.

6. The combination with a liquid container having a support secured thereto provided with a transverse sight-opening and a guide-opening extending upwardly from said sight-opening, of a liquid feed-device comprising two parts, one of said parts being secured to said container and having an axial inlet opening and the other being adjustably connected to said first-mentioned part and having an axial boss movably fitting within said guide-opening, said other part having an outlet opening axially through said boss, a valve-rod arranged axially within said casing and adapted to have opposite ends thereof co-act with said inlet and outlet openings, and a float secured to said valve rod.

In testimony whereof I affix my signature.

ARLINGTON L. BALL.
